UNITED STATES PATENT OFFICE.

JOHN F. O'CONNOR, OF CHICAGO, ILLINOIS, ASSIGNOR TO WILLIAM H. MINER, OF CHICAGO, ILLINOIS.

DRAFT-RIGGING FOR RAILWAY-CARS.

1,152,041.

Specification of Letters Patent.

Patented Aug. 31, 1915.

Application filed April 23, 1914. Serial No. 833,841.

To all whom it may concern:

Be it known that I, JOHN F. O'CONNOR, a citizen of the United States, residing at Chicago, in the county of Cook and State of Illinois, have invented a certain new and useful Improvement in Draft-Rigging for Railway-Cars, of which the following is a full, clear, concise, and exact description, reference being had to the accompanying drawings, forming a part of this specification.

My invention relates to improvements in draft rigging for railway cars.

The object of my invention is to provide a draft gear of simple construction and efficient operation.

In the drawings forming a part of this specification, Figure 1 is a side elevation, partly in central vertical longitudinal section, of a draft gear embodying my invention, and showing the parts in normal position; Fig. 2 is a horizontal section on line 2—2 of Fig. 1, showing the position of the parts in full buff; Fig. 3 is a cross section taken on line 3—3 of Fig. 1; Fig. 4 is a perspective view of the draft yoke.

Referring to the drawings, the numerals 5—5 indicate draft members, or parts of the car-frame to which the draft rigging is applied, 6 an upper stop member, and 7 a lower stop member, the said stop members being vertically spaced apart, and each consisting preferably of a channel-shaped member, the upper stop member 6 having the upturned flanges 8—8, and the lower stop member having the down-turned flanges 9—9, the said stop members being secured to the draft members preferably by the rivets 10—10 passing through the flanges and through adjacent portions of the draft members.

The draft yoke 12 is of the horizontal type and is mounted between the draft members, the limbs 13—13 thereof being received between the upper and lower stop members. The draft yoke 12 is forwardly provided with the transverse slots 14—14 adapted for the passage of the coupler key 15, the coupler key extending through the transverse slot 16 through the draw-bar 17 (only the rear end of the draw-bar is shown in the drawings) the end of the key 15 passing through slots 18—18 in the draft members, the said slots

18—18 being longitudinally extended to permit forward and rearward movement of the coupler key therein.

The draft gear illustrated by the drawings is of the tandem type, the front compression resisting member 19 consisting preferably of the outer spring 20 and the inner spring 21 nested therein. The rear compression resisting member 22 consists preferably of the outer spring 23 and the inner spring 24 nested therein. The front compression resisting member is mounted between the front follower 26 and the front intermediate follower 27. The upper and lower stop members are each provided with vertical openings 28—28, there being one in each stop member for each follower, the upper end of each follower being received in its appropriate slot of the upper stop member, and the lower end of each follower being received in its appropriate registering slot in the lower stop member. The transverse members forming the ends of the vertical slots in the stop members are the stop-shoulders for the followers. Thus there is provided for the front follower front, upper and lower stop-shoulders 30 and 31 respectively, upper and lower limiting stop-shoulders 32 and 33 respectively, for the front intermediate follower the intermediate upper and lower stop-shoulders 34 and 35 respectively, and the upper and lower limiting stop shoulders 36 and 37 respectively; for the rear intermediate follower the upper and lower intermediate stop-shoulders 37A and 38 respectively, and the upper and lower limiting stop-shoulders 39 and 40 respectively; for the rear follower the upper and lower rear stop-shoulders 41 and 42 respectively, and the upper and lower limiting stop-shoulders 43 and 44 respectively. The draft yoke 12 is provided with an intermediate connecting thimble 45, preferably integral with the limbs of the yoke, and preferably formed of an upper transverse web 46, a lower transverse web 47, and a vertical, preferably integral web 48. The limbs 13 of the yoke are rearwardly connected by the connecting member 49, preferably comprising the integral outer web 50 and the preferably integral filler web 51. The rear connecting member 49 and the

thimble 45 of the yoke are provided with longitudinal openings 52—52 to receive a bar 53, the said bar 53 entering the butt end of the draw-bar through the opening 54 in the rear face thereof at one end, and extending through the yoke at the other end, the yoke being provided with the boss 55 and a pin 56 passing through said boss and the bar 53 to prevent the accidental displacement of the bar. The followers are each provided with a longitudinal perforation 57 through which the bar 53 passes, there being provided a thimble or sleeve 58 between the followers of each set, each sleeve 58 receiving the bar 53 therethrough. Each sleeve 58 is surrounded by an inner coil spring, the inner coil spring being in turn surrounded by an outer coil. Each outer coil spring is supported by the lower stop member, and the outer coil through the inner coil and the sleeve supports the bar 52, the bar being also supported by the draw-bar and draft yoke, said bar 52 supporting the followers and preventing their accidental displacement. Thus through the springs and bar the followers are supported.

I claim:

1. In a draft rigging, the combination with draft sills, of stop members secured to said sills and arranged to form longitudinal guideways for a horizontal yoke, a horizontal yoke mounted in said guideways and supported along its edges by said stop members, followers, and means located within the sides of the yoke for supporting said followers. 30
2. In a draft rigging, the combination with draft sills, of upper and lower, spaced, horizontal stop members secured to said sills, a horizontal yoke supported between and by said stop members, followers within said yoke, and a longitudinally extending rod passing through the yoke and said followers and forming the entire support for the 45 latter. 40

JOHN F. O'CONNOR.
